(57) **CLAIM**

The ornamental design for an empanadas pet treat, as shown and described.

DESCRIPTION

FIG. 1 is top, front and left side perspective view of a first embodiment of an empanadas pet treat according to the new design;

FIG. 2 is a top plan view of the embodiment of FIG. 1;
FIG. 3 is a bottom plan view of the embodiment of FIG. 1;
FIG. 4 is a front elevation view of the embodiment of FIG. 1;

FIG. 5 is a back elevation view of the embodiment of FIG. 1;

FIG. 6 is a left side elevation view of the embodiment of FIG. 1;

FIG. 7 is a right side elevation view of the embodiment of FIG. 1;

FIG. 8 is top, front and left side perspective view of a second embodiment of an empanadas pet treat according to the new design;

FIG. 9 is a top plan view of the embodiment of FIG. 8;
FIG. 10 is a bottom plan view of the embodiment of FIG. 8;
FIG. 11 is a front elevation view of the embodiment of FIG. 8;

FIG. 12 is a back elevation view of the embodiment of FIG. 8;

FIG. 13 is a left side elevation view of the embodiment of FIG. 8;

FIG. 14 is a right side elevation view of the embodiment of FIG. 8;

FIG. 15 is top, front and left side perspective view of a third embodiment of an empanadas pet treat according to the new design;

FIG. 16 is a top plan view of the embodiment of FIG. 15;
FIG. 17 is a bottom plan view of the embodiment of FIG. 15;
FIG. 18 is a front elevation view of the embodiment of FIG. 15;

FIG. 19 is a back elevation view of the embodiment of FIG. 15;

FIG. 20 is a left side elevation view of the embodiment of FIG. 15;

FIG. 21 is a right side elevation view of the embodiment of FIG. 15;

FIG. 22 is top, front and left side perspective view of a fourth embodiment of an empanadas pet treat according to the new design;

FIG. 23 is a top plan view of the embodiment of FIG. 22;
FIG. 24 is a bottom plan view of the embodiment of FIG. 22;
FIG. 25 is a front elevation view of the embodiment of FIG. 22;

(Continued)

FIG. 26 is a back elevation view of the embodiment of FIG. 22;

FIG. 27 is a left side elevation view of the embodiment of FIG. 22; and,

FIG. 28 is a right side elevation view of the embodiment of FIG. 22.

The broken lines shown in the drawings illustrate portions of the empanadas pet treat that form no part of the claimed design.

The stippled shading and the line shading shown in FIGS. 1, 2, 4, 6, 7, 8, 9, 11, 13, 14, 20, 21, 27 and 28 represent a contrasting appearance.

The break lines shown in the middle portion of the empanadas pet treat in FIGS. 8-14 and 22-28 indicate that the appearance of any portion of the article between the break lines forms no part of the claimed design.

1 Claim, 12 Drawing Sheets
